Inventor:

Louis Bond Morgan,

By Counsel of First & Farley
Atty.

UNITED STATES PATENT OFFICE

2,065,607

COMBINATION RAZOR BLADE CONTAINER
AND DISPENSERLouis Bond Morgan, Chicago, Ill., assignor to
Montgomery Ward & Co., Incorporated, Chi-
cago, Ill., a corporation of Illinois

Application October 23, 1935, Serial No. 46,260

8 Claims. (Cl. 206—16)

The present invention relates to a combination razor blade holder and dispenser and has particular reference to an original package for new razor blades that may be sold to the public and 5 be utilized as a receptacle for old blades and thrown away when the new blades are all used.

Razor blades today are normally sold in small packages of five or ten blades each with every 10 blade contained in a separate sheath or envelope. After a blade has been used a few times it becomes dulled for shaving purposes and is ready for disposal. Care must be taken in the 15 disposal of these blades since severe injuries can be suffered from these used blades. Heretofore containers have been provided for this purpose made from earthenware or metal and sold separately to the purchaser for receiving the old 20 blades. When the container is filled it is thrown away and danger of injury to persons from these blades is greatly lessened.

While these separate containers are helpful, they are expensive, and, as they are bought only when needed, the user of the blades often finds himself without a receptacle and must use utmost care in disposing of the used blade or store 25 them some place until another receptacle can be purchased.

A principal object of this invention is to provide a razor blade dispenser that is easy to operate, and inexpensive and simple to manufacture. 30

Another object of this invention is to provide an original package for dispensing new blades and receiving old blades.

35 A further object of this invention is to provide with every package of blades sold an easy and safe means for the disposal of said blades when used.

Still other and further objects of my invention 40 will be pointed out or indicated hereinafter or will be apparent to one skilled in the art upon an understanding of the invention or its employment in practice.

One embodiment of my invention is set forth 45 in the drawing for the purpose of exemplification. It is to be understood that the invention is not limited to the exact form shown but may be embodied in other and similar structural forms coming equally within the scope of the 50 appended claims.

In the drawing:

Fig. 1 is a view of the combination dispenser and receptacle in elevation.

Fig. 2 is a view in elevation of the inner container member of said dispenser and receptacle.

Fig. 3 is a sectional view through the same taken on line 3—3 of Fig. 4 showing the inner member telescopically or slidably received within the outer cover.

Fig. 4 is a front view of said receptacle.

In a preferred embodiment of my invention, such as shown in the drawing, is shown an outer substantially cubical box member open at one end. Into this open-ended box member is slid a second substantially cubical member having an 10 inclined new razor blade holder and guideway sloping downwardly towards one face of said box member. A slot and thumb groove in the outer box member corresponding to the lower end of the guideway of the inner member permits the 15 manual withdrawal of a single blade at a time from said dispenser.

The inclined guideway terminates short of the rear end of the inner member leaving a passageway for the reception of used blades and both 20 the inner and outer box members are slotted at the upper end of this passageway so that used blades may be dropped therein. The whole space lying below the guideway is thus given over to the used blades. When the new blades have been 25 used and dropped into the used blade compartment, the entire box may be safely disposed of as easily as waste products about the house.

With reference to the drawing, the invention 30 may be embodied in an inner box-like member 10 having a body member formed substantially in the shape of a hollow cube. A razor blade guide 35 of the inner box member and the blades are preferably positioned vertically to the base of said member or stacked parallel to the front face of the same.

way or article holder 12 is disposed within this inner box-like member and arranged diagonally there-across to form a downwardly slanting holder for new blades. This guideway or chute 40 is of sufficient height to permit a plurality of blades inserted or stacked therein to move forwardly and downwardly along the guideway by the force of gravity toward the ejector end 14. To accomplish this end the floor and the ceiling 45 of the chute should preferably be parallel. The height of the chute may be less than the maximum width of the blades since the chute is slanted downwardly at an angle to the base 15

The chute 12 does not extend to the rear side 50 of the inner box-like member 10 but is enclosed by a backing member or blade supporting piece 16 which is attached to the upper face of the inner member. The chute 12 is supported from the upper face of the inner member at the junc- 55

tion of the backing piece 16 with the ceiling of the chute leaving, between the backing piece 16 and the rear face of the inner member a passageway 18 leading to a disposal chamber 20 below the chute 12. The upper face of the inner member 10 is slotted as at 21 to form an entrance to said passageway.

At one side of the forward end 14 of the chute 12 is mounted a guide member or deflector strip 10 22 causing the downwardly moving series of blades to be deflected toward the opposite side of the chute as they near the forward end thereof. The side of the chute opposite the guide member is left open so the blades are free to pass 15 therefrom.

An outer box-like member 24 similar to the inner member 10 in shape and open on its rearward face is provided to slidably receive the inner member therewithin. The lower forward 20 face 25 of the outer member 24, corresponding to the open side of the forward end of the chute 12, is cut away to form a thumb grip opening 26 and the side face 27 of the outer member is slotted to form an ejector slot 28. A blade 11 25 may be pressed sideways from the lower end of the chute 12 in the inner member 10 through the slot 28 when needed by the thumb.

The inner member 10 is telescoped within the outer member 24 with the lower end of the chute 30 12 forward. The open end of the chute 12 corresponds with the thumb grip opening 26 which is not large enough to permit blades within the chute to fall therethrough but only of such size as to admit the pad of the thumb or finger for 35 applying a sideways sliding pressure on the blade to press it through the slot 28.

The upper face 29 of the outer member 24 is slotted as at 30 to correspond to the slot 21 in the upper face of the inner member 10 forming 40 a continuous slot through both the inner and outer members to the passageway 18 and the disposal chamber 20.

The inner package may be made from a continuous piece of metal or cardboard which is 45 stamped or scored and folded to make the top and face walls, the chute member 12 and the base and back of the inner member 10 in an inexpensive and simple manner.

In assembling this device, the inner member 50 is laid upon its rear face and the chute 12 is loaded with the desired number of blades 11. The open end of the outer member 24 is then slid over the inner container so that the slot 30 therein corresponds to the slot 23 in the inner 55 member and the package is completed and ready for sale. A year's supply of blades may be sold in this way and disposed of one after another in a simple, safe and inexpensive manner.

I claim:

60 1. In a container of the type described, an inner container and an outer enclosure therefor, said inner container being provided with an inclined article-holding chute and a used article disposal chamber positioned beneath said chute having an opening in said container leading thereto, said outer enclosure having an ejector slot corresponding to the forward end of the chute in the inner container and an opening

corresponding to the disposal chamber opening when the inner container is fully inserted within said enclosure.

2. In a container of the type described a body portion substantially cubical in shape, a diagonally downwardly inclined article-holding chute within said container having an ejector slot at its lower end, a used article disposal chamber disposed within said container and separate from said chute, and a slot in said container leading 10 to said disposal chamber.

3. In a container of the type described an inner body portion having a downwardly inclined article-holding chute disposed therein and open at its lower end, article deflector means mounted 15 at one side of the lower end of said chute, a used article disposal chamber within said container, and an outer enclosure for said inner body portion, said enclosure having an article ejector means corresponding to the lower end of said 20 chute and positioned on the opposite side of said chute from said deflector means, and an article disposal slot leading to said disposal chamber.

4. In a container of the type described a hollow inner body portion having an inclined article-holding support member mounted therein, an article ejector slot at one side of the lower end of said support member, and article-deflecting means at the lower end of the other side of said support member for directing articles towards 30 said slot.

5. In a container of the type described an outer enclosure member open at one end and an inner container member slidably received therein, said inner container having article-supporting 35 means disposed therein and a used article disposal chamber adjacent to said supporting means but separate therefrom, said outer enclosure member having an article ejector slot for extracting articles from said article supporting 40 means and a used article disposal slot for inserting used articles into said disposal chamber.

6. In a container of the type described a container including base, back, top and one side wall, an article-supporting chute inclined upwardly from the base wall of said inner container, said chute terminating short of said back wall to form a passageway between the back wall and the rear of said chute, and an article disposal chamber disposed below said chute and 50 in communication with said passageway.

7. In a box-like dispensing and disposal container, a base portion, an article-holding chute extending upwardly from said base portion diagonally across said container, a disposal chamber 55 in that portion of said container not occupied by said disposal chute, and openings in said container cooperating with said chute and disposal chamber respectively for the removal and placement of articles.

8. In a box-like dispensing and disposal container, a base portion, an article-holding chute having a floor and ceiling and extending diagonally upwardly across said container from said base, the height of said chute between floor and 65 ceiling being less than the maximum vertical width of the articles therein stored.

LOUIS BOND MORGAN.
